UNITED STATES PATENT OFFICE.

GUSTAF E. SMITH, OF WORCESTER, MASSACHUSETTS.

BEDSTEAD-BRACE.

SPECIFICATION forming part of Letters Patent No. 684,556, dated October 15, 1901.

Application filed February 5, 1900. Serial No. 3,972. (No model.)

To all whom it may concern:

Be it known that I, GUSTAF E. SMITH, of the city and county of Worcester and State of Massachusetts, have invented certain new and 5 useful Improvements in Bed Attachments for Preventing the Rails Thereof from Spreading; and I do hereby declare that the following is a full, clear, and exact description thereof, reference being had to the accompanying drawings, forming a part of this specification, and in which—

Figure 1 represents a transverse section through a bed-frame and its spring with my improved attachment applied thereto. Figs. 15 2 and 3 represent, upon an enlarged scale, a plan and edge view, respectively, of the central portion of said attachment. All the following figures are also shown on the same enlarged scale. Figs. 4 and 5 are a plan and 20 edge view, respectively, of one of the end plates of the attachment; and Fig. 6 is a transverse section through one of the connecting-rods, showing an end view of one of the aforesaid end plates.

25 My invention relates more particularly to beds having wood rails.

The object thereof is to provide means for preventing the side rails of a bed from spreading or being forced outward, and said invention comprises a device constructed as herein set forth, and pointed out in the claim.

In order that others may better understand the nature and purpose of my said invention, I will now proceed to describe it more in detail.

35 In the drawings, A A represent the two side rails of a bed, B the cross-slats, and C the spring laid thereon. My improved attachment D is arranged, as before stated, under the bed, being extended across from one rail

40 A to the other and fastened thereto, as is shown in Fig. 1. Said attachment or holding device is so constructed that it may be ad-

justed in length to fit different widths of beds. It consists of the two rods a a', arranged in

45 line longitudinally and provided at the center with a turnbuckle b, having longitudinal holes through its ends to receive the inner ends of the rods, one being preferably a smooth opening to receive the headed end of rod a

50 and the other end threaded to receive the threaded end a² of rod a'. The outer end of

each rod is provided with a hook c, which is adapted to engage with one of the transverse holes d' in the angle-plates d d at the outer end of each rod. Said angle-plates each have 55 one end d² thereof bent at right angles to the body of the plate, and through said bent end is formed a hole d³ for the passage of the hooked end of each rod. In attaching the outer ends of the rods to said angle-plates the 60 hooks are passed first through the end openings d³ in the bent parts d² and then hooked into one or another of the holes d' in the body of said plates, as is shown in Figs. 4, 5, and 6. By thus making said attachment it is obvious 65 that the rods may be quickly hooked in place, are securely held when thus attached, and by loosening the device by turning the buckle b at the center said device may be easily and quickly adjusted to any ordinary width of 70 bed by hooking the ends of rods a a' into the proper holes d' in the angle-plates and afterward tightening the device taut by turning the central buckle b. The outer ends of the angle-plates may be attached to the bed- 75 rails A A by means of ordinary screw-eyes, the eye or ring thereof being passed through the outer hole in each plate and the screw turned into the bed-rail, as is shown in Fig. 1.

As is well known, considerable trouble has 80 been experienced by the central part of the side rails of a bed, especially those having wood rails, spreading and allowing the slats to drop down out of the bed, which objection, it will at once be apparent, is entirely obvi- 85 ated by the use of my invention. The device is inexpensive, easily applied, and may, as previously stated, be readily adjusted to fit an ordinary width of bed.

Having now described my invention, what 90 I claim therein as new, and desire to secure by Letters Patent, is—

The combination with the rails of a bed, of a device to prevent the spreading thereof, comprising a central turnbuckle having one 95 end provided with a threaded longitudinal opening and the other end with a smooth lon- gitudinal opening; a longitudinal rod having a hooked outer end and a threaded inner end adapted to fit in said threaded opening in 100 the turnbuckle; a longitudinal rod having a hooked outer end and a head on its inner end to

hold it from being pulled from the smooth longitudinal opening in the turnbuckle, two angle-plates, one at each end of the aforesaid rods, each having an opening in its angle part at 5 its inner end, to receive the rod, and a series of openings in the body thereof to receive the hook on the rod, and a screw-eye at the outer

end of each plate adapted to hook into one of the holes thereof and to be screwed into the bed-rail, substantially as set forth.

GUSTAF E. SMITH.
